DIAPER PAIL LID

Mark S. James, Jr., Pittsburgh, Pa., assignor to Mark Laboratories, Inc., Pittsburgh, Pa.

Filed July 9, 1964, Ser. No. 80,778

Term of patent 14 years

(Cl. D58—26)

Fig. 1.

Fig. 2.

Fig. 3.

I claim:

The ornamental design for a diaper pail lid, substantially as shown.
